CLOSURE

John R. Hoge, Toledo, Ohio, assignor to Owens-Illinois Glass Company, a corporation of Ohio

Application March 31, 1945, Serial No. 585,863

2 Claims. (Cl. 215—40)

1

My invention relates to closures for hermetically sealing jars, bottles and the like containers, and more particularly to the so-called side seal type wherein a sealing gasket, or ring, carried by the closure, firmly contacts an exterior sealing surface of the container immediately beneath the rim or mouth thereof.

It is an object of my invention to provide a closure of the above character in which the skirt portion is of such form and the sealing gasket is so positioned therein, that a satisfactory initial seal is effected simultaneously with the first positioning of the closure upon the mouth of the receptacle, and solely due to the weight of the closure which functions to press the rim of the container slightly into the gasket. This is of considerable importance and advantage in the vapor vacuum method of sealing food containers, wherein, for example, the jars are transported through a steam chamber to fill the head space with live steam and while yet in the live steam zone, receive closures from an inclined cap chute, such closures being drawn from the chute by engagement with the rim of the continuously moving containers. See Hohl Patent No. 2,357,826, issued September 12, 1944. It is important that the closures, incident to initial placement upon the containers, and prior to final attachment thereto, form a sufficiently effective seal to entrap a substantial volume of live steam in the head space and retain it therein during succeeding cap-applying operations.

To this end an area of that portion of the skirt immediately adjacent part of the gasket is spaced therefrom to a degree which enables the gasket to yield outwardly slightly incident to initial placement upon the container solely under the weight of the closure. Thus the gasket tends to wrap around the rim and provides an exceptionally wide initial sealing surface with the advantages stated heretofore.

It is also an object of my invention to provide a side seal type of closure, wherein the sealing gasket is so positioned and supported therein as to readily compensate to an unusual degree, for irregular, or out-of-round rims at the filling opening of containers, and thereby insure satisfactory initial sealing incident to the mere placement (without applied top pressure) of a closure upon the mouth and prior to the usual succeeding final pressing of the closure onto the container.

Further objects and advantages of my invention will be apparent or pointed out hereinafter.

In the accompanying drawings forming a part of my application:

2

Fig. 1 is a fragmentary side elevational view partly in section illustrating my closure attached to a receptacle.

Fig. 2 is a detail sectional view on an enlarged scale showing the initial position of the closure upon a receptacle prior to the application of top pressure thereto.

Fig. 3 is a view similar to Fig. 2 but showing a secondary sealing position of the closure as summed under initial top pressure applied thereto.

Fig. 4 is a fragmentary detail sectional view showing the closure in its final sealing position.

Fig. 5 is a view similar to Fig. 4 but shows the closure raised slightly as occurs incident to the building up of internal pressure, and the sealing gasket and groove in the receptacle securing the closure against complete displacement.

Fig. 6 is a fragmentary bottom plan view of the closure.

20 Closures of the type herein disclosed are ideally suited to the vapor vacuum sealing of jars, bottles, and the like receptacles, in that they may be easily and rapidly affixed to such containers while the latter are moving continuously or intermittently through a steam chamber, and as stated heretofore, function with exceptional efficiency to entrap and retain a substantial volume of live steam in the head space of the receptacles. An example of a machine for vapor vacuum sealing containers with closures of the type herein illustrated, is disclosed in the Hohl Patent No. 2,357,826, issued September 12, 1944. The containers filled, with the exception of a suitable head space, with the commodity to be preserved, 35 are carried through a steam chamber and near the exit end thereof remove a closure from an inclined delivery chute simply through engagement of the rim of the container with one edge of the closure which protrudes slightly below the chute. Forward travel of the container pulls the closure out of the chute. Thereupon the closure rests upon and initially seals the receptacle so as to entrap live steam in the head space. The container with the closure resting thereon is then 40 moved to a cap-affixing zone where a mechanical device presses the closure downwardly over the rim of the container and brings the sealing gasket into snug engagement with the external side sealing surface of the container.

45 My improved closure which is formed of sheet metal consists of a circular top portion 10 and a depending annular skirt 11, or flange which includes a lower gasket carrying part 12 concentric with and of somewhat greater diameter than an upper part 13, portions of which function to con-

strict or compress some of the sealing material or gasket 14 against the exterior sealing surface 15 of the receptacle 16.

The mouth or filling opening 17 of the receptacle is defined by a rim 18, or wall, the outer upper corner of which assumes the form of an annular bead 19, a portion of which functions as an initial sealing surface adapted for sealing contact with the gasket immediately upon receiving a closure and prior to any deliberate cap-affixing step. This initial sealing surface is spaced upwardly from the final or main sealing surface 16, by an annular groove 20, which under certain conditions hereinafter related, interlocks with a part of the gasket to secure the closure against complete displacement in the event excessive internal pressure is developed, either during the processing of a commodity, or later, as often occurs with coffee.

Returning to the closure construction, the upper part of the skirt is joined with the lower part by a generally radially extending annular step 21, which consists in effect of merging transversely curved flanges at the adjacent ends of the upper and lower parts of the skirt. The flange at the lower end of the upper part of the skirt constitutes a bead 21* which cooperates with the bead 19 of the receptacle mouth as and for a purpose to be described presently. With the exception of the gasket clamping or clinching bead 22 at the extreme lower end of the skirt, said lower part 12 is spaced from the gasket whereby to permit ready outward yielding of the gasket incident to initial placement of the closure upon the receptacle. To facilitate secure locking of the gasket and positive retention thereof against upward movement relative to the skirt, the continuity of the clamping bead may be interrupted by short transverse slits 23 which in effect provide an annular series of individual jaws 24 capable of tight engagement with the lower margin of the gasket. As shown, this gasket is of generally oblong cross section and contacts the skirt only at the lower beaded margin and at the extreme bottom end of the upper part of said skirt. The gasket is of the usual rubber, or composition having the characteristics of being compressible and resilient and capable of effectively sealing against the receptacle wall.

In the application of my closure to a receptacle, it is first placed upon the mouth thereof following filling with a commodity, and the introduction of a volume of live steam or vapor into the head space. It is important that this steam be retained against escape and to this end the present closure by reason of the resilience of the gasket and fact that it is not backed up by a rigid wall, performs perfectly. The gasket at its point of first contact with the so-called initial sealing surface on the bead 19, and solely because of the weight of the metal shell and gasket, yields outward and tends to wrap itself about the bead. Thus a wide annular seal is obtained at the outset. Moreover, the partially unsupported gasket compensates perfectly and completely for out-of-round rims and thereby further insures the necessary initial sealing of the receptacle. The vapor or live steam begins to condense immediately upon placement of the cap upon the rim of the receptacle, and as a result of the pressure differential further initially holds the closure in place.

The next step is to mechanically or otherwise press the closure downwardly over the rim. This moves the closure and gasket from the position

shown in Fig. 2, to that indicated in Fig. 3 wherein the gasket is pinched between the bead 18 on the container and the curved flange or bead at the bottom end of the upper part of the skirt. This largely determines the amount of the sealing gasket that will be compressed between the upper part of the skirt and the main side sealing surface 15 of the jar. Moreover, it increases the initial effective sealing area of the closure skirt and gasket, thus contributing further to the efficiency of the initial seal referred to heretofore.

Finally, the closure assumes its final sealing position (Fig. 4) wherein the gasket is held firmly against the external sealing surface 15 and under considerable compression between the lower area of the upper part of the skirt and the container wall. If the commodity is processed after sealing of the container, there may be developed such internal pressure as to push the closure outwardly from the Fig. 4 position. When this occurs, the gasket snaps into the groove beneath the bead and locks the closure against further displacement and prevents breaking of the seal. Thus blowing off of the cap under exceptionally high internal pressure is avoided. Following the processing operation (cooking at high temperature) the commodity and receptacle cool off, the internal pressure is again reduced, and the cap returns to its innermost position. In the case of coffee packaging, gases are ordinarily developed within the receptacle. Here again the groove and bead function to prevent breaking of the seal as indicated above.

It will be observed that the gasket is positioned at a definitely obtuse angle, this being conducive to easy initial placement of the closure over the mouth of a receptacle. Removal is facilitated by reason of the interrupted clinching bead and the presence of a pry-off ledge L in close proximity to said bead. By prying the skirt upwardly at two or three closely spaced points circumferentially of the bead, the vacuum may be broken gradually and while the cap is still held against blowing off, by the interlocking gasket and groove. Reseal is facilitated through the presence of the groove which securely engages with the gasket when the cap is forced onto the receptacle to the position indicated in Fig. 5.

Modifications may be resorted to within the spirit and scope of the appended claims.

I claim:

1. A sheet metal closure comprising a circular top portion, a depending annular skirt on said top portion including an upper part of the same diameter as the top portion substantially throughout its height, and a lower diametrically enlarged part, said enlarged part including an obtusely tapered lower portion the angle of which is such that an imaginary line extended upwardly and inwardly along the plane of the inner surface of said lower portion would substantially touch the interior of the closure at the juncture of said upper and enlarged parts, a sleeve gasket within the closure and normally contacting only said tapered lower portion and the extreme lower end of said upper part of the skirt, and means for securing the gasket against shifting bodily upward along the skirt.

2. A sheet metal closure comprising a circular top portion, a depending annular skirt on said top portion including an upper part of the same diameter as the top portion substantially throughout its height, and a lower diametrically enlarged part, said enlarged part including an

obtusely tapered lower portion the angle of which is such that an imaginary line extended upwardly and inwardly along the plane of the inner surface of said lower portion would substantially touch the interior of the closure at the juncture of said upper and enlarged parts, a sleeve gasket within the closure and normally contacting only said tapered lower portion and the extreme lower end of said upper part of the skirt and the lower marginal part of the tapered portion being curled to grip the gasket firmly and secure it against shifting bodily upward along the skirt.

JOHN R. HOGUE.
